UNITED STATES PATENT OFFICE.

IGNATZ MIENTKIEWICZ, OF WATERBURY, CONNECTICUT.

RAIL JOINT AND FASTENER.

1,409,058.

Specification of Letters Patent. Patented Mar. 7, 1922.

Application filed December 17, 1921. Serial No. 523,046.

To all whom it may concern:

Be it known that I, IGNATZ MIENTKIEWICZ, a citizen of Poland, residing at Waterbury, in the county of New Haven and State of 5 Connecticut, have invented certain new and useful Improvements in Rail Joints and Fasteners, of which the following is a specification.

This invention relates to certain new and 10 useful improvements in rail joint and fastener, and has particular reference to the idea of securing the meeting ends of rails to a joint chair without the employment of fastening bolts.

15 The primary object of the invention resides in the provision of a rail joint and fastener wherein the joint chair supporting the meeting ends of rails, carries a cam shaft adapted to be moved into engagement with 20 the rails to anchor the same to the chair.

A further object of the invention has reference to a rail joint and fastener wherein a chair supporting the meeting ends of rails, has a longitudinally extending cam shaft 25 journaled therein with a splice bar interposed between the cam portion of the shaft and the rails to be engaged by the cam for holding the rails anchored in the chair, cooperating rack teeth formed on the cam and 30 splice bar to prevent rotation of the cam shaft when the same is moved to a locked position with respect to the rails.

With these general objects in view and others that will appear as the nature of the 35 invention is better understood, the same consists in the novel construction, combination and arrangements of parts hereinafter more fully described, illustrated in the accompanying drawings, and pointed out in the 40 appended claims.

In the drawings forming a part of this application and in which like designating characters refer to corresponding parts throughout the several views,

45 Figure 1 is a top plan view of a rail joint and fastener constructed in accordance with the present invention showing the rails anchored to the chair, the locking cam shaft being illustrated in its open position by dotted lines,

Figure 2 is a side elevational view of the same,

50 Figure 3 is an end elevational view of the rail joint and fastener showing the cam shaft of the fastener interlocked with the splice bar.

Figure 4 is a cross sectional view taken on lines IV—IV of Figure 1, showing the cam shaft journaled in the chair and interlocked with the splice bar,

60 Figure 5 is a cross sectional view taken on line V—V of Figure 1, showing the cam shaft engaging the splice bar for moving the same into engagement with the rails,

Figure 6 is a detail sectional view showing 65 the position of the cam shaft when the splice bar is inserted in the joint chair, and

Figure 7 is a detail sectional view of a modified form of the invention showing an anchoring foot for the splice bar, received in 70 an opening provided in the rail chair.

Referring more in detail to the accompanying drawings there is illustrated a joint chair and fastener for railroad rails, the joint chair including a bottom wall 1 supported on cross ties 2 and having integral outer side rail-engaging flanges 3 for overlying and engaging the base flanges of the rails 4, the vertical webs 3^a of the flanges 3 engaging the webs of the rails 4 and having 80 spaced pins 5 extending through openings 6 in the webs of the rails, the meeting ends of the rails being received on the bottom wall 1 of the chair with the pins 5 of the flange webs 3^a received in the rail web openings to 85 prevent longitudinal movement of the rails relative to the chair.

As clearly shown in Figs. 4 to 6 the bottom wall 1 of the chair has a side extension 1^a opposite the rail-engaging flange 3, a perpendicular inwardly curved outer side wall 7 being carried by the extension wall 1^a with bearings 8 formed at the ends of the wall 7 for purposes presently to appear.

90 A longitudinally extending shaft 9 having a key end 9^a is journaled in the end bearing 8 of the side wall 7, the shaft 9 having a cam 11 secured thereto, or formed as an integral part thereof, intermediate the ends, the cam 11 when in the position shown in 100 Fig. 6 being spaced from the rails 4 a sufficient distance to permit the insertion of splice bars.

105 A splice bar 12 of the form best illustrated in Figs. 4 to 6 is positioned in the joint chair intermediate the cam shaft and the rails 4, the splice bar carrying pins 13 to be received in openings formed in the webs of the rails 4.

110 The splice bar 12 is placed in position as indicated in Fig. 6 and with the shaft 9 in the dotted line position shown in Fig. 1, said shaft being rotated to cause the cam 11

to engage the splice bar 12 and move the same into intimate engagement with the faces of the rails 4, and positioning the pins 13 in the rail web openings.

5 In order to prevent rotation of the cam shaft when the same is moved to engaging position with the splice bar, the outer face of the splice bar, at the end thereof spaced from the key end 9^a of the rod is provided with a vertical row of horizontally extending rack teeth 14, while the adjacent end of the cam 11 is provided with similarly formed rack teeth 15, the rack teeth 14 and 15 being interengaged by longitudinally shifting the shafts 9 and cam 11 carried thereby, the engaging teeth preventing rotary movement of the shaft 9 and effectively holding the meeting ends of the rails 4 properly assembled in the joint chair.

20 When the teeth 14 and 15 are engaged, the end 9^a of the shaft extends outwardly of the adjacent end wall 8 for the reception of a cotter pin 16 to hold the cam shaft in its locked position, and to prevent shifting movement thereof with a consequent disengagement of the teeth 14 and 15.

Should it be desired to remove the rails from the chair, the shaft 9 is shifted longitudinally to cause the disengagement of the 30 rack teeth 14 and 15, at which time the shaft may be rotated to disengage the cam 11 from the splice bar 12, returning the elements to the position shown in Fig. 6, and at which time, the splice bar 12 may be removed and the rails 4 similarly disengaged from the flange web 3^a of the joint chair. By continuing the longitudinal shifting movement of the shaft 9, the end thereof opposite the key portion 10 may be removed 40 from its end bearing 8, this movement being permitted by the relatively large bearing in the end wall 8 adjacent the key end 10 of the shaft. The shaft is then reversed in movement for entirely displacing the 45 same from the chair.

A modified form of the invention is shown in Fig. 7, wherein the elements of construction are similar to the preferred form, with the exception that the splice bar 12^a carries a 50 depending foot 17 to be received in an opening 18 provided in the bottom wall 1 of the joint chair, this engagement preventing creeping movement of the splice bar relative to the chair and may also be employed 55 in connection with the pins 13 illustrated in connection with the preferred form.

While the form of the invention herein

shown and described is what is believed to be the preferred embodiment thereof, it is nevertheless to be understood that various forms, modifications and arrangements of the parts may be made without departing from the spirit and scope of the invention as claimed.

What I claim is:—

65 1. A rail joint and fastener comprising a chair, meeting rail ends supported in the chair, a removable splice bar engaging one side of the rails positioned in the chair, a cam shaft journaled in the chair adapted to engage the splice bar to move the same into engagement with the rails, and cooperating means carried by the splice bar and cam shaft adapted for engagement when the cam shaft is longitudinally shifted, to prevent 70 rotary movement of the cam shaft.

2. A rail joint and fastener comprising a chair, meeting rail ends supported thereon, a splice bar for the rails, a longitudinally shiftable shaft journaled in said chair and a cam carried by said shaft adapted to engage the splice bar to move the same into engagement with the rails for anchoring the 80 rails to the shaft.

3. A rail joint and fastener comprising a 85 chair, meeting rail ends supported thereon, a splice bar for the rails, a longitudinally shiftable shaft journaled in said chair, a cam carried by said shaft adapted to engage the splice bar to move the same into engagement with the rails for anchoring the 90 rails to the shaft, and cooperating means carried by the splice bar and cam adapted for engagement when the shaft is longitudinally shifted, to prevent rotation of the 95 shaft.

4. A rail joint and fastener comprising a chair, meeting rail ends supported thereon, a splice bar for the rails, a longitudinally shiftable shaft journaled in said chair, a 100 cam carried by said shaft adapted to engage the splice bar to move the same into engagement with the rails for anchoring the rails to the shaft, and cooperating rack teeth 105 formed on adjacent faces of the splice bar and cam adapted for engagement when the shaft and cam are longitudinally shifted, to prevent rotation of the cam.

In testimony whereof I affix my signature.

IGNATZ MIENTKIEWICZ.
